UNITED STATES PATENT OFFICE

123,714

DESIGN FOR A DRESS OR SIMILAR ARTICLE

Gussie Gans, New York, N. Y.

Application September 11, 1940, Serial No. 94,952

Term of patent 3½ years

To the Commissioner of Patents:

Be it known that I, Gussie Gans, a citizen of the United States, residing at 12 East 86th Street, New York city, in the county of New York and State of New York, have invented a new, original, and ornamental Design for a Dress or Similar Article, of which the following is a specification, reference being had to the accompanying drawing, forming a part thereof.

I claim:

The ornamental design for a dress or similar article, substantially as shown and described.

GUSSIE GANS.
